UNITED STATES PATENT OFFICE.

RICHARD L. LLOYD, OF NEW YORK, N. Y., ASSIGNOR, BY MESNE ASSIGNMENTS, TO DWIGHT & LLOYD SINTERING COMPANY, INC., OF NEW YORK, N. Y., A CORPORATION OF DELAWARE.

METHOD AND APPARATUS FOR TREATING ORES.

Application filed April 28, 1922. Serial No. 557,048.

To all whom it may concern:

Be it known that I, RICHARD L. LLOYD, citizen of the United States, residing at New York, in the county of New York and State of New York, have invented certain new and useful Improvements in Methods and Apparatus for Treating Ores, of which the following is a specification, reference being had therein to the accompanying drawing.

My invention relates to a method of treating fine ores and other substances capable of being sintered, and to apparatus for carrying out such method, having the characteristics pointed out in the following specification.

In the drawings:

Fig. 1 is a view in side elevation of the apparatus.

Fig. 2 is a view in plan of the apparatus shown in Fig. 1.

Fig. 3 is a sectional view showing the delivery of the materials to the sintering hearth.

Referring to the drawings by numerals, 2 represents a sintering apparatus of a type known to the trade as the Dwight & Lloyd sintering machine. Patents 1,027,084 and 1,027,110 of May 21, 1912, to Dwight & Lloyd Metallurgical Company, illustrate and describe such apparatus, and reference is made thereto for details of construction not herein specifically illustrated and described. For the purposes of this invention it is only necessary to refer to the following parts.

A series of small individual ore carriers 3 are provided which are adapted to be arranged end to end and moved, as by drive mechanism designated 4, across the top of an air box 5 in which the pressure is reduced and suction created by a fan 6. This induces currents of air to pass through the fine ore with which the carriers 3 are filled, from a hopper 7, which in turn is kept supplied from a storage bin 8 by any suitable ore handling mechanism. The ore or other metalliferous material delivered from the hopper 7 is in a pulverulent or finely subdivided condition and carries a content that may be ignited and burned in the open air, to effect the sintering operation, in a well known manner. The carriers 3 after being filled are moved past an igniter (not shown) of any suitable or

known construction, where the combustible content of the charges in the carriers 3 is set on fire at the upper exposed surfaces of said charges. After this the carriers pass slowly over the open end of the air box 5 and the air currents produced by the fan 6 cause internal combustion to be carried on throughout the entire body of the charge in each carrier 3, sintering it and putting it into desirable condition for subsequent treatment, as for instance, in a metal-reducing furnace. The carriers 3 successively discharge their contents, after they have been sintered, as indicated at *a* in the drawing. During the sintering operation the particles of ore or other metalliferous substance with which the carriers have been filled become more or less agglomerated, so that the material discharged at the delivery end of the apparatus consists of particles of porous sintered material varying in size from fine grains to cakes or masses approximating in size the chamber of the carrier 3.

This material, the product of the apparatus 2, is delivered to a screen 13 which separates the larger particles of sintered material and delivers them to a conveyor 14, while the finer material that passes through the screen is delivered to a second screen 15. When the material treated in the apparatus 2 is to be passed to a blast furnace for further treatment the screen 13 may be of half inch mesh. The mesh of the screen 15 may be of $\frac{1}{4}$ th of an inch or smaller so that all the material from the machine 2 between $\frac{1}{4}$ th of an inch and a half inch in size will be delivered to the conveyor 16. This conveyor delivers to an elevator 18 which in turn discharges into a hopper 9 arranged to deliver its contents to the carriers 3 in advance of the delivery of material from the hopper 7.

In operating sintering machines such as shown herein it is found advantageous to cover the grates 11 of the carriers 3 with a layer of material inert as to atmospheric combustion in order that the grates may be somewhat protected against the intense heat incident to the sintering operation and the fine material being sintered be thereby prevented from being drawn through the grates 11 by the air blast. The finer products of the sintering machine, of a size separated by the screens 13 and 15, as described, are

2
found to be well adapted for use as the covering for the grates 11. The delivery opening of the hopper 9 is so restricted in size that only a thin layer 10, say of an inch in depth, is delivered upon the grates 11 as they successively pass beneath the hopper, and upon this layer the fine material from the hopper 7 is deposited.

The material that passes through the 10 screen 15, say $\frac{1}{4}$ th of an inch and under in size, is too fine to be used as a grate covering, since it would pass freely through the grate openings. It is, however, valuable material, since it carries its content of metal 15 and is in porous condition due to having been sintered, thus fitting it for subsequent treatment. The individual particles, however, are too fine for use in a blast furnace. I therefore deliver the final material that passes through the screen 15 to a collecting hopper 17 which in turn delivers to a conveyor 19. This conveyor, which may be of simple or complex construction and arrangement, is adapted to 20 deliver to the hopper where this finest portion of the product of the sintering machine is mixed with the raw ore and is a second time passed through the sintering machine 2 along with such raw ore, where 25 it becomes agglomerated with other particles and masses during the sintering operation. It is to be understood that the use of the phrase "raw ore" is not to be taken literally, for, while raw ore will be fed, in 30 certain operations, from the charging bin 8 to the feeding hopper 7, ore which has been subjected to preliminary treatment, and materials other than raw ore, will be handled according to my method in certain 35 operations.

By this method of procedure the entire product of the sintering machine is utilized, for, as will be understood, the particles constituting the layer 10, covering the grates, 40 adhere and agglomerate with the sintered charges in the carriers 3. In practice it has been found that about 75% of the product of the machine will be separated by the screen 13 and delivered to the conveyor 45 14; about 10% of the total product is taken out by the screen 15 to be utilized as the covering for the grate; and the remainder, approximately 15%, is of such fine character as to necessitate its being passed 50 through the sintering machine a second time to be further agglomerated. These proportions will, however, vary with the material being treated and also with the mesh 55 of the screens 13 and 15. It will be understood that if the quantity of the material 60 taken out by the screen 15 is not sufficient to form a proper protective covering for the grates 11, it may be supplemented by other suitable material fed to the hopper 65 16. 9. The invention herein described is not to

be limited in its use to the specific apparatus represented in the drawing and herein described, as that is employed in this case merely for the purpose of disclosing one practical embodiment of the invention. 70

What I claim is:

1. The herein described method of treating fine sinterable material consists in sintering the mass, then grading the sintered product according to the sizes of the particles thereof, using the material of one grade as a covering for the material holders during the sintering process, delivering the material of a finer grade to the material to be treated so it passes a second time through the sintering operation and conducting away the coarser material for later treatment. 75

2. The herein described method of treating sinterable ore which consists in passing it through a sintering machine, grading the product of such machine according to the size of the masses and particles delivered from the machine, separating the coarser masses and particles for later treatment, delivering the particles of intermediate size to the sintering machine to form a protective layer for the grates thereof, and delivering the finer particles to the machine along with the original material to be sintered. 85 90 95

3. The herein described method of treating sinterable ore which consists in sintering the original ore in a continuously operating machine, taking out of the product of the machine masses and particles of approximately a half inch in size and upward for later treatment as sintered material, taking out of the remaining product of the machine particles to approximately $\frac{1}{4}$ th of an inch in size and less and using as a protective layer for the grates of the sintering machine, and returning the remainder of the product to the material to be passed through the 100 105 machine to be sintered. 110

4. In sintering apparatus, the combination of a sintering machine, a grader to which the product of the machine is delivered, means for conducting away the coarser particles of the masses separated out by the grader for later treatment, conveying means for taking the particles of intermediate size delivered by the grader to the head of the machine and delivering them 115 upon the grates thereof as a protective layer, and conveying means for receiving and delivering the finer particles from the grader to the charging end of the machine. 120

5. In a sintering apparatus, the combination of a sintering machine, having a series of movable carriers for the material to be sintered, a charge hopper and a hopper for delivering a protective layer to the 125 130 grates of the machine, before the charges

are delivered thereon, a grading screen for receiving the product of the machine, means for conveying away the coarser masses and particles taken out by the grading screen for later treatment, conveying means for taking the particles of intermediate size separated by the grading screen and delivering to the hopper that delivers the protective layer to the grates of the carriers, and conveying means for delivering the finer particles separated by the grading screens to the charging hopper of the machine.

6. The herein described method of treating sinterable material which consists in sintering the original material, grading the sintered product into different sizes, using material of one size to cover the material holders during sintering, and subjecting the material of another size to a second sintering operation.

7. The herein described method of treating sinterable material which consists in sintering the original material, grading the sintered product into different sizes, using material of one size to cover the material holders during sintering, and delivering the material of another size to the original material to be treated so as to subject it a second time to the sintering operation.

8. The herein described method of treating sinterable material which consists in sintering the original material, grading the sintered product into different sizes, using material of one size to cover the material holders during sintering, and subjecting the material of a smaller size to a second sintering operation.

9. The herein described method of treating sinterable material which consists in sintering the original material, grading the sintered product into different sizes, using material of one size to cover the material holders during sintering, and delivering the material of a smaller size to the original material to be treated so as to subject it a second time to the sintering operation.

10. The herein described method of treating sinterable material which consists in sintering the original material, grading the sintered product into different sizes, using material of one size to cover the material holders during sintering, subjecting the material of another size to a second sintering operation, and carrying away a third size of the material for later treatment.

11. The herein described method of treating sinterable material which consists in sintering the original material, grading the sintered product into different sizes, using material of one size to cover the material holders during sintering, delivering the material of another size to the original material to be treated so as to subject it a second time to the sintering operation, and

carrying away a third size of the material for later treatment.

12. The herein described method of treating sinterable material which consists in sintering the original material, grading the sintered product into different sizes, using the material of an intermediate size to cover the material holders during sintering, delivering the material of a finer size to the original material to be treated so as to subject it a second time to the sintering operation, and carrying away the larger sizes of material for later treatment.

13. In apparatus of the class described, the combination of a sintering mechanism, grading mechanism to which the product of the sintering mechanism is delivered, conveyor means for delivering the material of an intermediate size to the grates of the sintering apparatus to form a protective layer, and conveyor means receiving the finer sizes from the grader and delivering them to the charging end of the machine.

14. In apparatus of the class described, the combination of sintering machines, a plurality of grading mechanisms to which the product of the sintering mechanism is delivered, conveyor means to deliver the material from one grading mechanism to the sintering grates as a protective layer, and conveyor means to deliver the product of another grading mechanism to the charging end of the machine.

15. In apparatus of the class described, the combination of sintering mechanism, grading mechanism to which the product of the sintering mechanism is delivered, means for carrying away larger sizes of the mass graded out for later treatment, conveyor means for delivering the material of an intermediate size to the grates of the sintering apparatus to form a protective layer, and conveyor means receiving the finer sizes from the grader and delivering them to the charging end of the machine.

16. In apparatus of the class described, the combination of sintering mechanism, a plurality of screens to which the product of the sintering mechanism is delivered, conveyor means to deliver the material from one screen to the sintering grates as a protective layer, and conveyor means to deliver the product of another screen to the charging end of the machine.

17. In apparatus of the class described, the combination of sintering mechanism, a plurality of screens to which the product of the sintering mechanism is delivered, means for carrying away the larger un-screened particles of the mass for later treatment, conveyor means to deliver the material from one screen to the sintering grates as a protective layer, and conveyor means to deliver the product of another screen to the charging end of the machine.

18. In apparatus of the class described, the combination of sintering mechanism, means for delivering original material thereto, grading mechanism to which the product of the sintering mechanism is delivered, conveyor means to deliver sintered material of one size to the sintering grates as a protective layer, and conveyor means for delivering material of another size separated by the grader to the original material delivering means. 15
19. In apparatus of the class described, the combination of sintering mechanism, grading mechanism to which the product of the sintering mechanism is delivered, means for conducting away for later treatment the large unscreened particles of the mass separated out by the grader, conveyor means to deliver the intermediate sizes of sintered material to the sintering grates as 20 a protective layer, and conveyor means for delivering the finer sizes of material to the charging end of the material for a second sintering operation. 25
- In testimony whereof, I affix my signature.

RICHARD L. LLOYD.

18. In apparatus of the class described, of the sintering mechanism is delivered, **15** the combination of sintering mechanism, means for delivering original material thereto, grading mechanism to which the product of the sintering mechanism is delivered, conveyor means to deliver sintered material of one size to the sintering grates as a protective layer, and conveyor means for delivering material of another size separated by the grader to the original material delivering means.

19. In apparatus of the class described, **20** the combination of sintering mechanism, grading mechanism to which the product

means for conducting away for later treatment the large unscreened particles of the mass separated out by the grader, conveyor means to deliver the intermediate sizes of sintered material to the sintering grates as a protective layer, and conveyor means for delivering the finer sizes of material to the charging end of the material for a second sintering operation.

In testimony whereof, I affix my signature. **25**

RICHARD L. LLOYD.

DISCLAIMER.
